SUGAR DISPENSER

Baruch Levy, Chelsea, Mass.

Application December 5, 1934, Serial No. 756,152

6 Claims. (Cl. 312—92)

The present invention relates to dispensing devices particularly adapted for the dispensing of cubes of sugar and is an improvement of my Patent 1,688,123 of October 16, 1928.

5 The objects of the invention are to provide a simple, dependable device of this character for dispensing one cube of sugar at a time; which will not clog; and in which the granules of sugar which fall away from the cubes drop to a collecting chamber from which they may be cleaned periodically.

The foregoing and other objects of the invention are attained by the novel construction and arrangement of the parts described in the following specification and shown in the accompanying drawing constituting part of this disclosure and in which :—

Fig. 1 is a front elevational view of a dispenser constructed in accordance with the invention.

20 Fig. 2 is a plan sectional view, to an enlarged scale, as taken along the line 2—2 of Figure 1.

Fig. 3 is a vertical sectional view as taken along the line 3—3 of Figure 1.

Fig. 4 is a similar view as taken at right angles 25 to Figure 3.

Fig. 5 is a sectional view showing the mechanism in dispensing position.

In the drawing the dispenser is shown as comprising a base 10, on which is removably supported a container 11 provided with a cover 12. These members may either be made of metal or 30 moulded material and if desired the container may be transparent for obvious reasons.

The base 10 is preferably formed as a chamber 35 13 having a removable bottom plate 14 and the top plate 15 of which is preferably provided with openings 15a.

The container 11 is, in this instance, formed with a cylindrical portion 16 at its lower end and 40 integrally formed therewith, is a cube receiving cup 17 communicated by the opening 18 in said cylindrical portion. The container 11 is preferably detachably secured to the base 10 as by means such as the illustrated threaded connection.

45 Within the cylindrical portion 16 is disposed an agitation and dispensing means comprising two opposed agitators 19 and 20 defining between them a cube receiving trough 21, the rear of which is the fixed curved wall 23, the front comprises a shutter portion 24 on the agitator 19 and a similar portion 25 on the agitator 20, and the bottom of which comprises the tiltable member 22 and the angularly disposed fixed chute 26.

In the present embodiment of the invention, 55 the member 22 is pivoted at 27 and is provided

with a pin 28 engaged in a slot 29 in the agitator 20.

The chute 26 is notched as at 30 to accommodate the lug 31 on the forward portion of the tiltable member 22.

If desired, instead of the lug 31 being of narrow width, the entire width of the member 21 may be utilized beneath the cube to be dispensed, to tilt it from its position on the chute 26.

The mechanism for reciprocating the agitators 19 and 20 and for tilting the member 22 is preferably housed within the base 10. This mechanism is operable through the medium of the actuating plunger 32 movable in the sleeve 33. The mechanism comprises a lever 34 pivoted 10 at 35 to the base and having a pin and slot connection 36 with the plunger 32; a down reaching extension 37 of the agitator 20 is also connected to the lever 34 and by means of the walking beam 38 pivoted at 39 to the slotted bracket 40, connection is made between the extension 37 and the extension 41 of the agitator 19.

Between a pin or the like 42 and the bottom of the plate 15, there is preferably provided a compression spring such as 43. A ledge 45, integral 25 with the fixed plate 15 is arranged between the front portions of the agitators 19 and 20 (Figs. 2 and 4), said ledge being supported in spaced relation with the chute 26, by walls 45a. This defines a chute area 18a immediately in front of 30 the trough 21.

In use, cube sugar is placed in the container through the top opening therein and the cover 12 replaced. The cubes will be promiscuously disposed within the container, but at least two 35 or three will assume the position shown in the Figure 3. Upon actuation of the plunger 32, the agitator 20 is moved downwardly and the agitator 19 moved upwardly. Since the shutters 25 and 24 are respectively integral portions of the agitators 20 and 19, these will also move apart to provide the opening shown in Figure 5 at 44 and since the pin 28 is carried down by its slotted connection with the agitator 20, the member 22 is tilted around its pivot 27 and the lug 31 tips 45 over the frontmost cube (Fig. 5) so it may pass through the opening 44, then through the opening 18 in the container and so drop into the receiving cup 17, the other cubes on the member 22 being moved to the rear of the device by the reversing of the angular disposition of the member 22.

Only one cube of sugar is dispensed in this manner for the top cross member of ledge 45 will prevent other cubes following by intercept- 55

ing those cubes disposed above it. Should a cube fall past the ledge 45 it would come to rest on the member 22 or cubes resting thereon, and because of the angular disposition of said member will 5 not tend to fall forward towards openings 44 and 18.

Upon release of the plunger 32, the spring 43 will return the parts to their normal position (Figs. 3 and 4) and it will be noted that possible 10 jamming or clogging of the device is obviated by the reciprocatory action of the agitators 19 and 20.

In order to further enhance the sanitary attributes of the device, the receiving cup 17 may 15 be provided with a spherically curved bottom whereby the tip of a teaspoon may be inserted under the dispensed cube of sugar to facilitate its removal therefrom without the aid of the fingers.

20 From the foregoing it can be seen that an improved device for the purpose has been provided, and although this disclosure is considerably detailed, no undue limitation, except those imposed by the prior art, should be interpreted 25 in the following claims.

Having thus described my invention, what I claim as new and desire to secure by Letters Patent, is:

30 1. In a cube sugar dispenser having a dispensing opening, spaced agitators vertically slidably mounted within the dispenser in such manner as to provide a trough between them, a floor for said trough including a tiltable member, closure members for said opening carried by said agitators and means to vertically reciprocate the agitators in opposite directions to open and shut the closure members and to move said tiltable member to dispense a lump of sugar as the closure members are opened.

40 2. In a cube sugar dispenser, spaced agitators slidably mounted in the dispenser providing a trough between them, a floor for said trough including a fixed portion and a tiltable member, a cube tipping extension on said tiltable member 45 movable through a notch in the fixed portion of the floor, and means to reciprocate the agitators and to move said tiltable member and said extension into angular position relative to said fixed portion.

50 3. In a lump sugar dispenser, spaced agitators slidably mounted in the dispenser providing a trough between them, a floor for said trough, comprising a tiltable member forming one por-

tion of said floor, and a fixed portion extending from the tiltable portion and provided with a notch, a lug on the tiltable member and positioned in the notch, and means to reciprocate the agitators and to tilt said tiltable member 5 whereby a cube of sugar is adapted to be tipped from its position on the fixed portion by the mentioned lug.

4. A sugar dispenser comprising a base, a container for cubes of sugar detachably secured to the base and having a dispensing opening, agitating means supported on the base and forming a trough therebetween, shutter means carried by the agitating means, a tilting floor for said trough having a cube tipping portion; and means 10 to reciprocate the agitating means and thereby open the shutter means, and to tilt the floor of the trough whereby a cube of sugar in said trough is tipped by the cube tipping portion through the opening provided by the shutter 15 means and through the opening in the container.

5. A sugar dispenser comprising a base, a container for cubes of sugar detachably secured to the base and having a dispensing opening, agitating means supported on the base and forming a trough therebetween, shutter means carried by the agitating means, a tilting floor for said trough having a cube tipping portion and means 20 comprising mechanism in the base operable by plunger means carried by the base to reciprocate the agitating means and thereby open the shutter means, and to tilt the floor of the trough whereby a cube of sugar in said trough is tipped by the cube tipping portion through the opening 25 provided by the shutter means and through the opening in the container.

6. A sugar dispenser comprising a base, a container for cubes of sugar detachably secured to the base and having a dispensing opening, agitating means supported on the base and forming a trough therebetween, shutter means carried by the agitating means, a tilting floor for said trough having a cube tipping portion, a mechanical connection between said floor and one of said 40 agitating means, and means to reciprocate the agitating means and thereby open said shutter means and tilt said floor, whereby a cube of sugar in said trough is tipped by the cube tipping portion through the opening provided by the shutter 45 means and through the opening in the container.

BARUCH LEVY.
